CIRCUIT BREAKER

William H. Nash and Raymond J. Bronikowski, South Milwaukee, Wis., assignors to McGraw-Edison Company, Milwaukee, Wis., a corporation of Delaware
Filed Dec. 17, 1959, Ser. No. 860,214
2 Claims. (Cl. 200—116)

This invention relates to circuit breakers and, more particularly, to circuit breakers which have particular but not exclusive application to the protection of electrical apparatus such as transformers.

Distribution class transformers are often provided with circuit breakers which open the secondary circuit upon the occurrence of a fault across the secondary leads or when long continued overloads heat the transformer to a point where there is likelihood that its insulation will fail. For this purpose, therefore, circuit breakers of this type are provided with thermal and overcurrent responsive elements adapted to open the circuit breaker contacts upon the occurrence of such overloads.

It has been found desirable, however, in certain applications where continuation of service is imperative that, such circuit interrupters operate only upon the occurrence of a fault.

It is an object of the invention to provide a new and improved circuit breaker for use in oil-immersed transformers which is responsive solely to fault currents in the secondary leads or extreme overloads.

It is another object of the invention to provide for use in an oil-immersed transformer a circuit breaker having a thermal element responsive to the flow of load current wherein means are provided to compensate for variations in ambient oil temperature.

These and other objects of the invention will become apparent from the detailed description of the invention taken in view of the accompanying drawings in which:

FIG. 1 is a vertical elevation view partly in section of the circuit breaker embodying the instant invention;

FIG. 2 is a front view of the circuit breaker shown in FIG. 1;

FIGS. 3, 4 and 5 show the circuit breaker operating mechanism in certain of its positions;

FIG. 6 is a top view of the circuit breaker's temperature responsive elements; and

FIG. 7 is a view taken along lines 6—6 of FIG. 5.

In general terms the invention comprises a circuit breaker for protecting electrical apparatus immersed in dielectric oil and having a first thermal-current responsive means operable to open the circuit breaker contacts and disposed beneath the surface of said oil and in circuit with said apparatus whereby it is subjected to the current flowing in said apparatus and the temperature of said oil. A second thermal-current responsive means, connected to operate in opposition with said first means, is also disposed beneath the surface of said oil but electrically insulated from said apparatus so that at least a portion of the effect of said oil temperature on said first means is cancelled.

The circuit breaker chosen to illustrate the instant invention is a 2-pole automatic trip-free device which is illustrated in detail in copending application Serial No. 831,424, and which is assigned to the assignee of the instant invention.

Referring to FIGS. 1 and 2, the circuit breaker mechanism is shown mounted on a suitable base 10 of moulded insulating material and each pole includes a contact assembly 12 and an overcurrent responsive assembly 14. A common operating and latch assembly 16 holds each of the contact assemblies 12 in closed position and is operable to release said contact assemblies upon the actuation of either of the overcurrent assemblies 14.

2

Each of the contact assemblies 12 includes a movable contact member 22 and a cooperating fixed contact 24 which is mounted on base 10. A U-shaped metallic frame member 26 is rigidly secured to the base and has a transverse pivot pin 27 mounted near its lower extremity for pivotally supporting a contact carrier member 28 formed of a suitable molded insulating material and which carries each of the movable contact members 22 in a contact housing 29 disposed at each of the opposite ends of a transverse connecting portion 30 so that the movable contact members 22 are operated in unison.

As seen in FIGS. 1, 6 and 7, the overcurrent responsive assemblies 14 each include a pair of parallel bimetallic elements 32 and 33 which are affixed at one end to the rear of base 10 by rivets 34. The free ends of elements 32 and 33 are each connected to the upper surface of the lower-most portion 36 of an upwardly extending angular insulating link 35 and electrically connected by a conductive bridging member 40.

20 A second pair of parallel bimetallic elements 32A and 33A are disposed below said first pair and in opposed relation thereto. The rear ends of each of the second pair of elements 32A and 33A are also secured to the base 10 by rivets 34 and are electrically insulated from members 32 and 33 by a cylindrical insulating block 38 disposed between said ends and an insulating sleeve 39 surrounding rivet 34. In addition, the opposite ends of members 32A and 33A are connected to the lower surface of link portion 36 to provide a mechanical connection between the free ends of the opposed pairs of bimetallic elements while electrically insulating them.

30 Carried at the upper end of insulating link 35 is a rearwardly extending trip bracket 41 for threadably receiving an adjusting trip pin 42 that engages the upper surface of a latch plate 43 pivotally mounted at 44 on frame 26. The latch plate 43 has a depressed central portion 45 which carries an L-shaped latch member 46.

Referring now in particular to FIGS. 1, 2, 3, 4 and 5, the operating and latch assembly 16 is shown to include an inverted U-shaped operating member 50 having an offset transverse connecting portion 51 at its upper end and having its lower ends 52 pivotally received in recesses 53 formed in base member 10. A latching mechanism 55 is disposed between the legs of operating member 50 and includes a latch arm 57 which carries a latch tip 58 at one end and which is pivoted at its other end around a fixed axis by means of a transverse pin 60 extending between the upright portions of frame 26. An arc shaped link 62 is pivotally connected at one end to the latch arm 57 and at its other end to an inverted L-shaped holding element 64 which is pivotally mounted on a transverse pin 65 fixed in frame 26. Holding element 64 is connected to movable contact carrier 28 by a toggle linkage 67 comprising a pair of parallel upper toggle links 68 which are pivotally connected at 69 to the midpoint of said element and a lower toggle link 71 pivotally connected at 72 to movable contact carrier 28. The other ends of these toggle links are pivotally connected together by means of a knee pin 74. A pair of parallel overcenter springs 76 connect knee pin 74 to the transverse portion 51 of operating member 50.

65 The operation of latching mechanism 16 will now be described with regard to FIGS. 1, 2, 3, 4 and 5. As shown in FIG. 1 the arm 78 of an operating crank 79 is rotatable in the plane of the drawing by an operating handle (not shown) disposed in the exterior of the apparatus being protected. Arm 78 is connected to operating member 50 by means of an operating rod 80 and an operating link 82 which threadably receives the lower end of operating rod 80 in one end and which is pivotally connected at its other end to the transverse connect-

ing portion 51 by means of a U-shaped bracket 83 and a pin 84.

FIG. 3 shows the operating mechanism in its unlatched position with the circuit breaker contacts open. In order to close the circuit breaker contacts from this position the operating member 50 must first be rotated in the clockwise direction until the mechanism is latched as shown in FIG. 4 and then rotated in a counter-clockwise direction closing the contacts as shown in FIGS. 1 and 5.

More specifically, clockwise rotation of arm 78 pivots operating member 50 in a clockwise direction within recesses 53. As member 50 pivots, its transverse portion 51 forces holding element 64 to rotate about pin 65 so that its upper end is moved downwardly and to the right as viewed in FIG. 3. A link 62 transmits the movement of holding element 64 to latch arm 57 thereby rotating it in a clockwise direction around pivot pin 60. As latch arm 57 rotates latch tip 58 engages latch 46 to pivot latch plate 42 in a counter-clockwise direction around its pivot points 43. After latch tip 58 has cleared latch 46, the latter is returned to its position shown in FIG. 4 by a biasing spring 86 which extends between upwardly extending arm 87 on latch plate 43 and bracket member 88 rigidly secured to the base 10. The return of latch plate 42 to its initial position secures the latching assembly in its latched position with the contacts open as shown in FIG. 4.

In order to close the contact assembly 12 after the latching assembly has been made rigid, operating arm 78 is rotated in a counter-clockwise direction to pivot operating member 50 in a counter-clockwise direction in recesses 53. As operating member 50 rotates the upper ends of overcenter springs 78 are moved to the left as viewed in FIG. 4 by transverse portion 51, while their lower ends momentarily remain stationary. Because the upper ends of springs 78 are rotating in an arc that is longer than their initial length, they will be extended thereby storing energy for rapidly closing the contacts and separating them rapidly upon tripping.

When the line of action of overcenter springs 76 passes the upper pivot point 69 of toggle link 68, they will become overcentered causing knee pin 74 to snap from its position shown in FIG. 4 to its position shown in FIGS. 1 and 5. This brings lower link 71 into toggle with upper link 68 thereby snapping the movable contact carrier 28 in a counter-clockwise direction about pivot pin 27 to close movable contact 22.

The operating sequence during manual opening of the main contacts 12 is the direct opposite of the closing operation just explained. Here the operating arm 78 is pivoted in a clockwise direction thereby moving the upper end of operating member 50 to the right as viewed in FIG. 1. When the line of action of overcenter springs 76 passes pivot point 69, the toggle will be broken and knee pin 74 will snap from its position shown in FIGS. 1 and 5 to its position shown in FIG. 4. The latch arm 57, however, will remain latched as shown in FIG. 4.

Referring now to FIGS. 1, 2 and 6, the electrical current path through each pole of the device is shown to be from a first conductive member 90 secured to fixed contact 24; through the fixed and movable contacts 24 and 22; through the second conductive member 91 secured to movable contact 22; through a flexible conductive member 92 secured at one end to conductive member 91 and at its other end to a third conductive member 93 affixed to bimetallic element 32; through conductive member 40 and bimetallic member 33 and finally to a fourth conductive member 95 connected to the second of the upper bimetallic elements 33. It can be seen, however, that the insulating members 36, 38 and 39 prevent any current flow in bimetallic elements 32A and 33A.

If the device is used to protect a distribution transformer, it is normally mounted below the surface of dielectric oil 96, as shown in FIG. 1, by means of a bracket

member 97 secured to the under side of base member 10. As a result, the bimetallic elements 32, 32A, and 33 and 33A, are exposed to the heat of this ambient oil. Also, bimetallic elements 32 and 33 are each subjected to heat produced as a result of their impedance to the flow of load current. However, because bimetallic elements 32A and 33A are electrically insulated from bimetallic elements 32 and 33 they are subjected only to the heat of the oil 96.

10 Bimetallic elements 32 and 33 are arranged so that upon the occurrence of an overload or the heating of oil 96 they tend to deflect downwardly as viewed in FIG. 1. Bimetallic elements 32A and 33A are so arranged, on the other hand, that they will tend to deflect upwardly in 15 opposition to bimetallic elements 32 and 33 when oil 96 becomes heated. It can thus be seen that by suitably proportioning the bimetallic elements, any tendency of bimetallic elements 32 and 33 to deflect downwardly as a result of an elevated oil temperature, can be cancelled by 20 the corresponding tendency of bimetallic elements 32A and 33A to deflect upwardly. However, because bimetallic elements 32A and 33A are electrically insulated from the load current, the entire assembly will deflect downwardly as a result of the heat developed in elements 25 32 and 33 caused by the flow of the load current.

As bimetallic elements 32 and 33 deflect downwardly, as viewed in FIG. 1, there will be a corresponding downward movement of trip pin 42 to rotate latch plate 43 in a counterclockwise direction around pivot 44. If the load 30 current exceeds the minimum setting of the device this rotation of latch plate 43 will be sufficient to release latch arm 57 so that overcenter springs 76 are free to contract, moving knee pin 74 from its position shown in FIGS. 1 and 5 to its position shown in FIG. 3, thereby breaking 35 the toggle linkage 67. This rotates the movable contact carrier 28 in a clockwise direction from its closed to its open position shown in FIG. 3 whereby the circuit is interrupted. The movement of knee pin 74 also rotates holding element 64 and latch arm 57 in a clockwise direction. Thus, the tripping action just described returns each 40 of the members of the operating assembly 16 from their positions shown in FIGS. 1 and 5 to their original positions shown in FIG. 3.

It can be seen from the foregoing discussion that regardless of the temperature of oil 96 the latching mechanism can only be tripped upon the occurrence of a fault current. This insures that service will continue during periods of expected overload.

The amount of downward deflection of the bimetallic 50 elements for any given current value, and hence, the magnitude of the overcurrent necessary to trip the device, may be adjusted by varying the initial rotation of latch plate 42 through the agency of the threaded trip pins 40.

While the invention has been described in relation to 55 one particular type of circuit interrupter, it will be understood that the invention has application as well to other types of circuit interrupters utilized to protect oil-immersed electrical apparatus.

We claim:

60 1. In a circuit interrupter for protecting an electrical transformer immersed in dielectric oil, the combination of a base, fixed and movable contact means mounted on said base, latch means for holding said movable contact means in closed position, a first bimetallic element in circuit with 65 said transformer and immersed beneath the surface of said dielectric oil, said first bimetallic element being secured near one of its ends to said base and having its other end coupled to said latch means and operable upon a predetermined deflection to release said movable contact means, a second bimetallic element secured at one end to said base and disposed beneath the surface of said oil in substantial parallelism with said first bimetallic element and electrically insulated therefrom, electrical insulating means connecting the other ends of each of said 70 bimetallic elements, said first and second bimetallic ele-

ments having substantially identical thermal characteristics and being arranged for deflection in opposite directions, whereby the effect of said oil temperature on said first bimetallic element is substantially cancelled.

2. In a circuit interrupter for protecting an electrical transformer immersed in dielectric oil, the combination of a base, fixed and movable contact means mounted on said base, latch means for holding said movable contact means in closed position, a first linear bimetallic element in circuit with said transformer and immersed beneath the surface of said dielectric oil, said first bimetallic element being affixed at one end to said base and having its free end coupled to said latch means and operable upon a predetermined deflection to release said movable contact means, a second linear bimetallic element secured at one end to said base adjacent the fixed end of said first bimetallic element and disposed beneath the surface of said

10

5

oil, said second bimetallic element being disposed adjacent said first bimetallic element in substantial parallelism therewith and electrically insulated therefrom, electrical insulating means connecting the free ends of each of said bimetallic elements, said first and second bimetallic elements being substantially identical and arranged for deflection in opposite directions, whereby the effect of said oil temperature on said first bimetallic element is substantially cancelled.
